L. HUMPHREYS

FLYING BALL

Filed Dec. 23, 1927

Inventor

L. Humphreys

By *Watson E. Coleman*

Attorney

UNITED STATES PATENT OFFICE.

LIDA HUMPHREYS, OF BUTTE, MONTANA.

FLYING BALL.

Application filed December 23, 1927. Serial No. 242,225.

This invention relates to toys, and particularly to toys for children.

The general object of the invention is to provide a ball of relatively soft material so constructed that it will amuse children by being thrown into the air or whirled in the air.

My invention is illustrated in the accompanying drawing, wherein:—

Figure 1 is a perspective view of a ball 10 constructed in accordance with my invention;

Figure 2 is a sectional view through the ball and arrow;

Figure 3 is a plan view of the blank from 15 which the arrow is formed.

Referring to this drawing, 10 designates a ball which may be formed of rubber, cotton or any other suitable material and be either solid or hollow. This ball 10 preferably has a cover, designated 11, which may be made of leather, yarn, cloth or may be a crocheted cover.

Extending through the ball is the similitude of an arrow, preferably made of a folded piece of patent leather or enamel-coated cloth or like material. This is so shaped as to provide a body more or less in the form of an arrow, having a head 12 and the bifurcated "feathers" 13. This "arrow", as before 25 stated, is formed of patent leather or enamel covered cloth longitudinally folded upon itself and extending through the ball. Attached to the ball is a cord 14, which at its end remote from the ball may be provided 30 with a ring 15 through which the fingers of the hand may be inserted.

The purpose of the device is to amuse children and to this end the ball may be thrown into the air or whirled in the air by 40 holding the string attached to the ball. It will be understood that the ball may be either solid or hollow, and that the arrow and ball may be made either large or small. Through the ball passes an arrow of textile 45 fabric, as before described, and the cord 14 preferably passes through the arrow and through the ball. The cord may have any desired length, and preferably on the end of

the cord there is a small ring by which the ball may be whirled. By whirling the ball, 50 provided it carries the arrow, a humming sound will be produced that has been found extremely attractive to children. When the ball is thrown into the air, the arrow seems to give the ball an added flying power and 55 the arrow is made of cloth or other flexible material in order that there shall be no danger of injuring a child who is playing with it. The arrow is held firmly in place by having the cord 14 pass through each end 60 of it close to the ball. The arrow also gives an ornamental quality to the ball and it may be of any desired color.

While I have illustrated one particular form of arrow, I do not wish to be limited to 65 this as the arrow might be made in different forms from that shown without departing from the spirit of the invention.

I claim:—

1. A toy for children comprising a ball 70 formed of an inner core and an outer covering of relatively soft material, a cord attached to the ball, and a member extending through the ball and projecting on opposite sides thereof, said member being folded longitudinally and having the similitude of an arrow.

2. A toy of the character described comprising a ball of soft material and a member extending diametrically through the ball and 80 formed of textile fabric folded upon itself, the member projecting beyond the ball on each side, and a cord attached to the ball and passing through the ball and said member.

3. A toy for children comprising a ball 85 of soft material, a cord attached to the ball, and a member extending through the ball and projecting on opposite sides thereof, said member being folded longitudinally and having at one end a head and at the other 90 end the similitudes of feathers, the cord extending through the ball and said member.

In testimony whereof I hereunto affix my signature.

LIDA HUMPHREYS.
